US00D705651S

(12) **United States Design Patent**
Neumann et al.

(10) **Patent No.:** US D705,651 S
(45) **Date of Patent:** ** May 27, 2014

(54) **TRIGGER**

(75) Inventors: **Peter M. Neumann**, Racine, WI (US);
Aaron J. Munsinger, Elk Mound, WI (US); **Wilhelmus Johannes Joseph Maas**, Someren (NL); **Robert C. Martineau**, Chippewa Falls, WI (US)

(73) Assignee: **S.C. Johnson & Son, Inc.**, Racine, WI (US)

(**) Term: **14 Years**

(21) Appl. No.: **29/423,521**

(22) Filed: **Jun. 1, 2012**

(51) LOC (10) Cl. **09-07**

(52) U.S. Cl.

CPC **B05B 11/3057** (2013.01)

USPC **D9/448**

(57) **CLAIM**

The ornamental design for a trigger, substantially as shown and described.

DESCRIPTION

FIG. 1 is an isometric view of a trigger according to the present invention;

FIG. 2 is a front elevation view of the trigger of FIG. 1; FIG. 3 is a right side elevation view of the trigger of FIG. 1, the left side view being a mirror image thereof;

FIG. 4 is a top plan view of the trigger of FIG. 1;

FIG. 5 is a bottom plan view of the trigger of FIG. 1; and, FIG. 6 is a rear elevation view of the trigger of FIG. 1.

The broken lines in the drawings represent unclaimed environmental subject matter and form no part of the claim.

1 Claim, 5 Drawing Sheets

US D705,651 S
